UNITED STATES PATENT OFFICE.

THOMAS K. CUMMINS, OF ST. PAUL, MINNESOTA, ASSIGNOR TO NORTHERN MALLEABLE IRON COMPANY, OF ST. PAUL, MINNESOTA, A CORPORATION OF MINNESOTA.

CONCRETE INSERT.

Application filed July 24, 1926. Serial No. 124,579.

My invention relates to concrete inserts such as are intended to be set into concrete floors, walls, ceilings, and the like to facilitate the attachment of various articles.

5 One of the objects of the invention is to provide a simple, practical and inexpensive construction of form of concrete insert.

Another object of the invention is to arrange for the introduction of the nut or other 10 part which is to be inserted in the insert to make connection, after the insert is in its position imbedded in the floor or wall or other part.

Another object of the invention is to arrange 15 for the ready adjustment of the bolt or hanger or other part which is to be connected to and supported by the insert, and particularly to arrange for the vertical, lateral and angular adjustment of said bolt or hanger.

20 In the accompanying drawings:

Fig. 1 is a view showing a concrete insert embodying my invention and also a portion of the wall or ceiling in which the same is imbedded, also the temporary or false work 25 used in connection with the wall or ceiling.

Fig. 2 is a view of said insert looking upwardly from below the same.

Fig. 3 is a longitudinal section of the insert and

30 Fig. 4 is a cross section taken on line 4—4 of Fig. 3.

Referring to the drawings I show a concrete insert 1 made of metal or other suitable material and preferably of somewhat elongated form. This insert has its body provided with an upper chamber or recess 2 and a lower chamber or recess 3. The top 4 preferably projects laterally so as to assist in holding or anchoring the device in position.

40 The upper chamber or recess 2 is to receive the upper end of the bolt or part to be supported by the device, such, for example, as the bolt or pipe 5, vertical adjustment of the bolt or pipe being permitted by the entry of the 45 upper end of the same more or less into said upper chamber 2.

The lower chamber 3 is to receive the holding member of the supported structure, such, for example, as the nut 6 on the end of bolt

50 5. A longitudinally extending slot 7 is formed in the lower part of the device so as to permit the longitudinal movement of bolt 5 to accommodate lateral adjustment of the same. This slot 7 is of sufficient width and 55 the chamber 3 of sufficient size as to permit

the nut 6 to be pushed into chamber 3 by passing it through slot 7 and then turning it so that said nut will be lodged in recess 3 in its normal transverse or holding position as shown in Fig. 1. This permits the nut 6 to be 60 inserted into the device after the latter is imbedded in position in the wall or floor.

As a matter of further improvement the device is preferably provided with an upwardly inclined or curved end portion 8, the 65 chamber 3 being correspondingly inclined at 9 and the wall 10 between chambers 2 and 3 also preferably having an upwardly inclined end portion 11. This permits the bolt 5 or other supported part to be swung from the 70 vertical as shown in Fig. 1 and consequently allows angular adjustment of the bolt or other supported part, thus arranging for angular accommodation for the part or structure supported. In this way it will be seen 75 that various adjustments of the bolt or other support are provided for, the device allowing such part to be adjusted vertically and also laterally, that is, more or less horizontally and also angularly, thereby giving the device 80 a very extended and universal use and permitting its accommodation to many and various types of structures and its use in many different arrangements and circumstances.

It will be understood that changes and 85 modifications may be made without departing from the spirit of the invention.

What I claim is:

1. A device of the class specified having an elongated nut chamber extending throughout the length of the device and opened at one end and curved upwardly at the other end and also having longitudinally extending nut guides extending along the bottom of said nut chamber throughout substantially 90 its entire length, said guides being also turned upwardly at one end in correspondence with the upturn of said nut chamber, whereby the nut may be adjusted in said chamber and along said guideway and will give its supported member substantially vertical or inclined positions accordingly as the nut is in the longitudinally extending or upwardly inclined portion of the nut chamber.

2. A device of the class specified having an 105 elongated nut chamber and an elongated bolt slot communicating therewith, said slot being formed by shoulders or guideways for the nut extending substantially throughout the length of the nut chamber and said device 110

having other longitudinally extending shoulders also extending substantially the entire length of the nut chamber in position above the position which would be occupied by the nut when in said chamber, whereby said nut may be adjusted to any desired position in the nut chamber longitudinally of the device and also whereby the bolt or other supported member may be adjusted vertically with reference to the nut in any position to which the nut may be adjusted.

3. A device of the class specified having a body provided with upper and lower chambers with a slot between them and also having a slot in said lower chamber for the reception and movement of a bolt, the end portion of said body being inclined upwardly to form means for securing angular as well as vertical and lateral adjustment of the bolt or like device.

4. A device of the class specified having upper and lower elongated chambers, both of whose bottom walls have portions which are substantially horizontal and other portions of which are inclined upwardly, said lower chamber having an opening therein through which a supporting member may be inserted.

5. A device of the class specified having upper and lower chambers, both of whose bottom walls have portions which are substantially horizontal and corresponding portions which are inclined upwardly, said lower chamber having an opening therein through which a supporting member may be inserted.

6. A device of the class specified comprising upper and lower chambers the end wall of the device being cut away at one end of the lower chamber whereby said chamber is open

at one end and closed at the other, said lower chamber having an opening therein through which a supporting member may be inserted.

7. A device of the class specified comprising upper and lower chambers whose bottom walls are substantially horizontal for a portion of their length and are inclined upwardly at one end, said bottom walls being provided with slots which are wide enough to accommodate the bolt but not wide enough to accommodate the nut on the bolt.

8. A device of the class specified comprising a housing having substantially vertical side walls and a top wall forming upper and lower chambers, said housing having a slot in its lower face communicating with the lower chamber and also having a slot between said upper and lower chambers to accommodate the bolt, but to prevent passage of the nut, one end of said housing having an upturned portion to incline said chambers upwardly and being provided with an outwardly and downwardly projecting inclined member to permit the inclination of the bolt.

9. A device of the class specified having a nut chamber inclined upwardly to cause inclination of the nut and bolt, said device also having a projecting portion provided with an inclined interior surface for the accommodation of the bolt when arranged at an angle, said nut chamber having an opening in its bottom through which a nut may be introduced and held in place to cooperate with a bolt.

In witness whereof I have hereunto subscribed my name this 16th day of July, A. D. 1926.

THOMAS K. CUMMINS.
